(57) **CLAIM**

The ornamental design for an electrical contact, as shown and described.

DESCRIPTION

FIG. 1 is a front, top and left side perspective view of an electrical contact showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

In the drawing views, the even-broken line showing of the environment is for illustrative purposes only and forms no part of the claimed design. The dash-dot line represents the boundary of the claimed design.
